UNITED STATES PATENT OFFICE.

EDWIN H. ROBERTS, OF DENVER, COLORADO, ASSIGNOR TO JESSIE H. ROBERTS, OF DENVER, COLORADO.

SIGNAL FOR VEHICLES.

1,250,661.

Specification of Letters Patent. Patented Dec. 18, 1917.

Application filed November 11, 1915. Serial No. 60,811.

To all whom it may concern:

Be it known that I, EDWIN H. ROBERTS, a citizen of the United States, residing at the city and county of Denver and State of Colorado, have invented certain new and useful Improvements in Signals for Vehicles; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The object of my invention is to provide a signal for automobiles or other vehicles operable from the steering wheel of the latter to indicate to anyone in front or approaching from the rear that the driver of 20 the vehicle intends to turn to the left, and for this purpose I mount a casing upon the rear left-hand fender of the said vehicle, said casing having a night signal located therein and a day signal pivotally mounted 25 on its top, both signals being visible from the front and rear, and means mounted upon the steering wheel for controlling both signals, said means being operable without removing either hand from the 30 said wheel.

Having briefly outlined my improved construction, I will proceed to describe the same in detail, reference being made to the accompanying drawing, in which is illustrated an embodiment thereof. In this 35 drawing,—

Figure 1 is a rear view of a vehicle equipped with my improvement.

Fig. 2 is a sectional view in elevation of 40 the signal mechanism and a diagrammatical view of the means for controlling the same.

Fig. 3 is a side view of the signal proper.

Fig. 4 is a cross sectional view taken on the line 4—4, Fig. 2, looking in the direction of the arrow.

Fig. 5 is a detail view showing the blank from which the signal plate is formed.

Let the numeral 5 designate a casing open at the bottom, and whose depending sides 6 are bent outwardly at 7 and perforated to receive bolts 8 which also pass through registering perforations formed in the fender 9. Nuts 10 are applied to the free extremities of these bolts.

55 Secured to the top of the casing 5 by

means of screws 12, is a bar 13 having its extremities bent upwardly at 14 parallel to each other, and perforated to loosely receive a pintle 15. A signal 16 composed of a plate preferably painted red upon both sides, is pivotally mounted upon said pintle and is adapted to normally lie flat above the casing. The bottom of the signal 16 is offset inwardly at 17, recessed at 18, and cut at 19 and 20 to form four lips or 60 projections, the two outer lips 21 being shorter than the two inner ones, which are designated by the numeral 22. The lips 21 are bent around the pintle 15 so as to form a square in cross section (see Figs. 3 65 and 4), while the lips 22 are passed under the pintle and bent upwardly, their free extremities being bent around and clenched upon a pin 23 which is loosely supported in the upper extremity of an actuating arm 70 24. This actuating arm extends downwardly through an opening in the top of the casing, and its lower extremity is pivotally connected within the latter at 25 with the bifurcated extremity of an armature 26 75 whose opposite extremity is pivotally connected at 27 with a bracket 28 secured to one of the sides of the said casing.

A coil spring 29 surrounds the arm 24 within the casing, its upper extremity bearing against the top of the latter and its lower extremity resting upon an annular shoulder formed upon the lower portion of the said arm 24.

Located in close proximity to the said armature is a magnet 30 which is secured to the under surface of the top of the casing by one of the screws 12. The magnet is provided with a core 31 adapted to attract the armature 26 when the said magnet is energized. An electric light socket 32 is also secured to the under surface of the top of the casing by means of screws 33, and is adapted to receive an electric light bulb 34. The light will occupy that portion of the 100 interior of the casing which will be outermost when the device is mounted upon the fender of the vehicle. In the front and rear sides of the casing, assuming that it is applied to the fender, are openings 35 located 105 opposite the light bulb.

Two guides 36 are secured interiorly to the casing, and are oppositely disposed adjacent each opening 35. These guides are inclined upwardly away from each other, 110

and are adapted to receive a transparent plate 37 preferably red in color, and which will cover the openings 35, the said plate having a portion of its side edges tapering 5 toward the bottom so that it can be readily inserted in the guides 36. By virtue of this construction it is only necessary to slide the plates 37 upwardly a short distance, approximately a quarter of an inch, in order 10 to withdraw the same.

In the inner side of the casing adjacent the magnet 30 is an opening 38, through which is inserted a perforated plug 39 composed of insulating material, said plug having 15 a collar adapted to engage the outside of the casing adjacent the periphery of the opening 38. The portion of the plug extending into the interior of the casing is exteriorly threaded to receive a fitting 40 interiorly threaded for this purpose. This 20 fitting is also composed of insulating material, and bears against the inner surface of the casing adjacent the opening 38 therein.

25 Contacts 41 and 42 are mounted upon the fitting 40, the contact 41 being connected by a conductor 43 with one pole 3 of a suitable electric source 44, while the contact 42 is connected by a conductor 45 with a 30 contact 46 located upon the steering wheel of the vehicle, both of said conductors adapted to pass through the perforation in the plug 39. Pivotaly connected with the contact 46 is one extremity of a switch arm 47, 35 its opposite extremity adapted to engage the contacts 48 and 49 also located upon said steering mechanism, the contact 48 being connected by a conductor 50 with the opposite pole 51 of the source of electricity 44.

40 The contact 41 is also connected with one pole of the magnet 30 by a conductor 52, while the contact 42 is connected with the opposite pole of said magnet by the conductor 53. The lamp is arranged in the same 45 circuit by means of conductors 54 and 55 which are respectively connected with the conductors 52 and 53.

From the foregoing description it is believed that the use and operation of my 50 device will be readily understood. When the machine approaches a corner and the driver desires to turn to the left, he merely moves the switch arm 47 from the dotted line to the full line position as shown in Fig. 2, 55 this operation being possible without taking either hand off the steering wheel, since said switch mechanism is mounted upon the rim of the latter. It is evident that when the switch is in the full line position in Fig. 2 60 the circuit will be closed through the lamp and magnet whereby the lamp is lighted and the magnet energized. The core of the magnet will then draw the armature up to the position illustrated in Fig. 2, and thus 65 the arm 24 will be forced upwardly raising

the signal 16 to the signaling position and notifying anyone in the front or rear that the driver intends turning to the left.

The signal 16 will, of course, only be visible in the day time while the lamp signal 7 will be noticeable both day and night, and particularly so at night.

Attention is called to the fact that the spring 27 is slightly compressed at all times, that is, even when the armature is in its 7 normal position, and is particularly adapted to secure the armature and its connections against snaking, and thus prevents rattling of the parts. No auxiliary means is necessary to force the armature downwardly when the magnet is deenergized since it will fall of its own accord, and such movement will be facilitated by the rush of air against the forward surface of the signal 16. 8

Attention is further called to the fact that it is my intention to open and close the circuit a number of times in rapid succession whereby the light will blink and the plate signal flop up and down for the purpose 9 of more efficiently calling attention to the contemplated movement of the vehicle. It will also be apparent that a push button or other suitable mechanism may be employed instead of the switch disclosed upon the 9 drawing.

Having thus described my invention, what I claim is,—

1. A device of the class described comprising a casing mounted upon the fender 1 of the vehicle, a signal plate pivotally mounted upon top of said casing and normally adapted to lie flat, a lamp signal located within the casing which has openings in its sides through which said lamp is exposed, a magnet also secured within the casing, an armature located below the magnet and having one extremity pivotally connected with the casing, an actuating arm whose lower extremity is pivotally connected with the opposite extremity of the armature and whose upper extremity projects through and above the said casing and is pivotally connected with the signal plate, a spring surrounding said actuating arm 1 within the casing, its upper extremity bearing against the top of the latter and its lower extremity resting upon an annularly arranged collar formed upon the lower portion of said arm, a normally open circuit 1 in which the lamp signal and magnet are located, said circuit also including a source of energy carried by the vehicle, and means mounted upon the steering wheel of the latter for closing the circuit to light the lamp 1 and energize the magnet whereby the arm will be actuated to raise the plate to the signaling position.

2. An automobile signal comprising a casing mounted upon the rear fender of the 1

machine, a lamp signal located within the casing which has openings in its sides through which said lamp signal is exposed, a magnet also secured within the casing, an 5 armature located below said magnet and having one extremity pivotally connected with the casing, an arm whose lower extremity is pivotally connected with the opposite extremity of the armature and whose upper 10 extremity projects through and above the casing and is perforated, a pin inserted through said perforation and loosely supported therein, an angle bar mounted upon top of the casing adjacent the upper extremity of said arm, a pintle loosely supported by the angle bar, a signal plate hav- 15

ing lips formed upon its lower edge, certain of said lips adapted to pass under the pintle and upwardly into rigid engagement with the said pin, while the other lips loosely 20 surround the said pintle, a circuit in which the light signal and magnet are located, and a source of energy and controlling means mounted upon the machine and also located in said circuit. 25

In testimony whereof I affix my signature, in presence of two witnesses.

EDWIN H. ROBERTS.
